[57] CLAIM

The ornamental design for a foldable seat for use primarily in a canoe, as shown and described.

DESCRIPTION

FIG. 1 is a perspective view of the foldable seat for use primarily in a canoe showing my design;

FIG. 2 is a front elevational view thereof;

FIG. 3 is a rear elevational view;

FIG. 4 is a side elevational view thereof;

FIG. 5 is a top view;

FIG. 6 is a bottom view thereof; and

FIG. 7 is a perspective view of the foldable seat for use primarily in a canoe in the folded position.

FIG. 2

*FIG. 3**FIG. 4**FIG. 5**FIG. 6*

FIG. 7
